UNITED STATES PATENT OFFICE.

HERMAN C. PRIEBE, OF BLUE ISLAND, ILLINOIS.

TRUCK FRAME.

Application filed March 16, 1922. Serial No. 544,184.

To all whom it may concern:

Be it known that I, HERMAN C. PRIEBE, citizen of the United States, residing at Blue Island, in the county of Cook and 5 State of Illinois, have invented a certain new and useful Improvement in Truck Frames, of which the following is a full, clear, concise, and exact description.

My invention relates to trucks for rail-10 way cars, one object of the invention being to provide an improved form of bolster column and an improved means of assembling the same with the balance of the frame. In carrying out this feature of my invention 15 I desirably employ two bolster columns in each truck side frame, these bolster columns being spaced apart to receive the spring plank therebetween and each being assembled, at least at one end, and preferably at each end with the balance of the frame.

In the preferred embodiment of the invention each bolster column is formed with pins at its ends that enter sockets formed 25 in the adjacent arch bars and there is a retainer for further securing the lower end of each bolster column in assembly with the balance of the frame, these retainers being riveted or otherwise secured to the spring 30 plank that is interposed therebetween.

The invention also has for its object the provision of an improved assembly of the journal boxes with the side frame. In carrying out this feature of my invention I employ 35 two threaded bolts at each end of the side frame, these bolts passing through the upper arch bar and the tie bar and being in clamping relation to the adjacent journal boxes. A single plate is also employed 40 at each end of the side frame with which the corresponding bolts have threaded engagement, this single plate replacing the individual nuts that are customarily employed and co-acting with both bolts to prevent the loosening of either.

The invention will be more fully described in connection with the accompanying drawings showing the preferred embodiment thereof and in which Fig. 1 is a side 50 view, partially in section, of a truck constructed in accordance with the invention; Fig. 2 is a sectional plan view on line 2-2 of Fig. 1; Fig. 3 is a longitudinal sectional view of the central portion of the side frame 55 showing different relations assumed by the

bolster columns in the process of assembling the same with the balance of the truck frame; Fig. 4 is a sectional view on line 4-4 of Fig. 1; Fig. 5 is a perspective view of one of the bolster columns and the retainer therefor, in separated relation; and Fig. 6 is a perspective view illustrating the threaded plate employed for holding one pair of journal box assembling bolts from turning.

Like parts are indicated by similar characters of reference throughout the different figures.

The truck side frame illustrated includes an upper arch bar or compression member 1, a lower arch bar 2, and a tie bar 3. In the preferred embodiment of the invention the bolster columns that intervene between the arch bars are formed separately from both of the arch bars, though the invention is not to be thus limited. These bolster columns are illustrated at 4 and 5 and are preferably formed of castings whose upper ends overhang the upper arch bar, being sufficiently offset for this purpose. The overhanging portions of the bolster columns are formed with depending pins 6 which are receivable in sockets 7 in the upper arch bar. Pins 8 are formed upon the lower ends of the bolster columns, being receivable within sockets 9 that are formed in the lower arch bar 2 and the tie bar 3.

In order that the bolster columns may perform their function as space preserving and strain transmitting struts they are constructed to engage the bottom side of the upper arch bar and in order that the bolster columns may be assembled with the upper arch bar in a manner to afford this engagement thereof with the arch bar, the upper ends of the bolster columns are formed with inclined ledges. The upper pin 6 and the ledge 10 of each column are spaced apart sufficiently to permit the positioning of the upper arch bar between this pin and ledge when the bolster column is inclined in the process of assembly as indicated at the left in Fig. 3. When the bolster column has been vertically positioned with its upper pin in the corresponding socket, the inclined ledge 10 of such column engages the bottom side of the arch bar. When both bolster columns have been thus assembled with the upper arch bar, both arch bars are brought into their final relative positions in a man- 110

2
ner to place the lower pins 8 in their sockets 9. The columns are preferably symmetrically arranged.

A shoulder 11 is at the top of each lower 5 pin 8 and bears upon the lower arch bar to co-operate with the corresponding inclined ledge 10 in effecting engagement between each bolster column and the arch bars.

Any suitable or usual form of spring 10 plank 12 is interposed between the lower ends of the bolster columns. A retainer 13 is employed for fixing the assembly of the lower end of each bolster column with the balance of the truck frame, each bolster column 15 having its lower end between the adjacent outer side of the spring plank 12 and the corresponding retainer which is riveted or otherwise secured to the spring plank. Each retainer has an overhanging portion 20 14 which rests upon the shoulder 11 and engages the adjacent upright side of the corresponding bolster column whereby movement of the lower end of such bolster column vertically or horizontally with respect to the 25 balance of the truck frame is prevented.

Any suitable type of truck bolster may be employed, the truck bolster 15 illustrated being carried upon springs 16 that are bottomed upon the spring plank. Journal 30 boxes 17 are provided at the ends of each truck side frame, each journal box being assembled with its end of the side frame by means of two bolts 18 which are passed through the converged ends of the arch bars 35 at the top of the journal box and loosely through the tie bar 3. The lower ends of the bolts 18 of each box are threaded and have threaded engagement with a plate 19 common thereto that underlies the adjacent end of the tie bar. Each journal box 40 is disposed between its bolts 18 that pass through journal box ears 20. When the bolts are screwed home the underlying plate is brought into clamping engagement with the under side of the tie bar, this clamping plate co-operating with both bolts to prevent either bolt from coming loose. As a 45 further safeguard, the bolts pass through pieces of strip metal 21 that are interposed between the heads of the bolts and the upper arch bar, these pieces of strip metal being finally brought into Z-form to have their ends engage the heads of the bolts and the upper arch bar after the bolts have been 50 fully tightened to guard against turning of the bolts. While the lower arch bar preferably terminates above the journal boxes, the invention is not to be thus limited.

It will be observed that the bolts 18 also 60 assemble the arch bars and the tie bar together, these elements all constituting parts of the side frame and I desire to claim the use of the plate 19 in conjunction with the bolts when these bolts are employed in this way whether they are also employed for as-

sembling the journal boxes with the side frame or not.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Pat- 75 ent the following:—

1. A truck side frame including an upper arch bar; a lower arch bar; and a bolster column formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the upper arch bar between the upper pin and the inclined ledge when the bolster column is inclined in the process of assembly. 90

2. A truck side frame including an upper arch bar; a lower arch bar; and a bolster column formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the upper arch bar between the upper pin and the inclined ledge when the bolster column is inclined in the process of assembly, the lower pin upon the bolster column being receivable in the lower arch bar from above the same, there being a shoulder at the top of this lower pin that bears upon the lower arch bar. 110

3. A truck side frame including an upper arch bar; a lower arch bar; and two symmetrically related bolster columns each formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the up- 120 130

per arch bar between the upper pin and the inclined ledge when the bolster column is inclined in the process of assembly.

5. A truck side frame including an upper arch bar; a lower arch bar; and a bolster column assembled with said arch bars and in pin and socket connection with the same, in combination with a spring plank; and a retainer secured to the spring plank, the lower end of the bolster column being held between said spring plank and retainer.

35 6. A truck side frame including an upper arch bar; a lower arch bar; and a bolster column formed with pins that enter sockets formed in said arch bars to effect assembly of the bolster column and arch bars, in combination with a spring plank; and a retainer secured to the spring plank, the lower end of the bolster column being held between said spring plank and retainer.

45 7. A truck side frame including an upper arch bar; a lower arch bar; and a bolster column formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the upper arch bar between the upper pin and the inclined ledge when the bolster column is inclined in the process of assembly, in combination with a spring plank; and a retainer secured to the spring plank, the lower end of the bolster column being held between said spring plank and retainer.

65 8. A truck side frame including an upper

arch bar; a lower arch bar; and a bolster column formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the upper arch bar between the upper pin and the inclined ledge when the bolster column is inclined in the process of assembly, the lower pin upon the bolster column being receivable in the lower arch bar from above the same, there being a shoulder at the top of this lower pin that bears upon the lower arch bar, in combination with a spring plank; and a retainer secured to the spring plank, the lower end of the bolster column being held between said spring plank and retainer.

9. A truck side frame including an upper arch bar; a lower arch bar; and two symmetrically related bolster columns each formed with pins that enter sockets formed in said arch bars to effect assembly of the bolster column and arch bars, the bolster column including an inclined ledge at its upper end that is engageable with the under side of the upper arch bar, the bolster column overhanging the upper arch bar; the pin which enters the socket in the upper arch bar being carried by the overhanging portion of the bolster column; the upper pin and inclined ledge being spaced apart sufficiently to permit the positioning of the upper arch bar between the upper pin and the inclined ledge when the bolster column is inclined in the process of assembly, in combination with a spring plank between the bolster columns; and a retainer secured to each outer side of the spring plank and having the lower end of the adjacent bolster column interposed between the same and the adjacent side of the spring plank.

10. A truck side frame including an upper arch bar; a lower arch bar; and two symmetrically related bolster columns each formed with pins that enter sockets formed in said arch bars to effect assembly of the bolster column and arch bars, the bolster column including an inclined ledge at its upper end that is engageable with the under side of the upper arch bar, the bolster column overhanging the upper arch bar, the pin which enters the socket in the upper arch bar being carried by the overhanging portion of the bolster column, the upper pin and inclined ledge being spaced apart sufficiently to permit the positioning of the upper arch bar between the upper pin and the inclined ledge when the bolster column 115 120 125 130

4

is inclined in the process of assembly, the lower pin upon the bolster column being receivable in the lower arch bar from above the same, there being a shoulder at the top 35 of this lower pin that bears upon the lower arch bar, in combination with a spring plank between the bolster columns; and a retainer secured to each outer side of the spring plank and having the lower end of the adjacent 40 bolster column interposed between the same and the adjacent side of the spring plank.

10 11. A truck side frame including an upper arch bar; a lower arch bar; and a bolster column between the arch bars and having 45 pin and socket connection at its lower end 50 with the lower arch bar, in combination with a spring plank; and a retainer secured to one side thereof, the lower end of the column being held between said retainer and the 55 spring plank.

12. A truck side frame including an upper arch bar; a lower arch bar; and two bolster columns between the arch bars and having pin and socket connection with the 55 lower arch bar, in combination with a spring 60 plank between said bolster columns; and retainers, one secured to each side of the spring 65 plank, the lower end of each bolster column being secured between the spring plank and the adjacent retainer.

13. A truck side frame including an upper arch bar; a lower arch bar; and a bolster column between the arch bars and separately formed from the lower arch bar, in

combination with a spring plank; and a retainer secured to one side thereof, the lower end of the column being held between said retainer and the spring plank.

14. A truck side frame including an upper arch bar; a lower arch bar; and two bolster columns between the arch bars and separately formed from the lower arch bar, in combination with a spring plank between 45 said bolster columns; and retainers, one secured to each side of the spring plank, the lower end of each bolster column being secured between the spring plank and the adjacent retainer.

15. A truck side frame including an upper arch bar; a lower arch bar; and a bolster column assembled with said arch bars and in pin and socket connection with the same, in combination with a retainer, the lower end of the column having a portion 55 interposed between the retainer and lower arch bar.

16. A truck side frame including an upper arch bar; a lower arch bar; and a bolster column assembled with said arch bars and in pin and socket connection with the upper 60 arch bar, in combination with a retainer, the lower end of the column having a portion 65 interposed between the retainer and lower arch bar.

In witness whereof, I hereunto subscribe 65 my name this tenth day of February, A. D. 1922.

HERMAN C. PRIEBE.
